UNITED STATES PATENT OFFICE

ENRICO MORELLI, OF CINCINNATI, OHIO

STUCCOING AND PLASTERING MACHINE

Application filed November 23, 1928. Serial No. 321,378.

My invention relates particularly to machines for applying plaster or stucco or the like material to buildings, such as is described in my application Serial No. 306,487.

5 The objects of the invention are to provide a simple, efficient, and durable device for utilization in economically and effectively applying plaster, stucco, and the like plastic material to the surface of the corners of 10 rooms; and to provide means whereby the material being applied is automatically conveyed from a supply hopper, spread upon said surface and smoothed thereon.

The invention consists in the combination 15 of the parts, in the detail of the construction, and in the arrangement of the elements, as claimed.

In the drawings:

Fig. 1 is a side elevation of the invention 20 with the parts broken away and showing parts in dotted lines;

Fig. 2 is a section taken on a line corresponding to 2—2 in Fig. 3, with parts broken away;

25 Fig. 3 is a transverse section taken on a line corresponding to 3—3 in Fig. 2; and

Fig. 4 is a section taken on a line corresponding to 4—4 in Fig. 3.

In the preferred construction of the invention, I provide the plastering machine 1 having the frame 2 comprising the spaced apart rectangular vertical supports 3, the top plate 4. A base not shown, is suitably connected with the lower ends of the supports 3.

30 Slidably mounted on the supports 3 is the carriage 5. The frame 6 of the carriage comprises the spaced apart sides 7 and 8 each having the spaced apart rectangular holes 9 and 10 therein slidably receiving the supports 3. The sides 7 and 8 are maintained in fixed relation with respect to each other as by the spaced apart and parallel horizontal struts 11, 12, and 13, extending intermediate the sides 7 and 8 and integral therewith.

35 Intermediate the holes 9 in the side 7 of the frame 6 is the integral hub 14 slidably receiving the vertical screw 15 having its lower end journaled in a suitable bearing in the base. The upper end of the screw 15 is journaled

the holes 10 in the side 8 of the frame 6 is the integral internal threaded hub 16 threaded to the vertical screw 17 having its lower end journaled in a suitable bearing in the base. The upper end 18 of the screw 17 is journaled 55 in a bearing in the top plate 4, whereby rotation of the screw 17 is adapted to impart vertical movement to the carriage 5.

The screws 15 and 17 are rotated by suitable outside source of power supply, which 60 may be an electric motor mounted upon the base.

Secured to the arms 19, which extend inwardly from the sides 7 and 8 of the carriage 5, is the plaster or other plastic material hopper 20 having the orifice 21 in its bottom 22 for the purpose of permitting plaster to be discharged from the hopper onto the plurality of plaster conveying belts 23 which are mounted adjoining each other in the circumferential grooves 24 and 25, respectively, in the front and rear rollers 26 and 27.

The belts 23 are adapted to automatically convey the dried plaster, accumulating when the machine stands idle after use, from the 75 machine when the latter is operated whereby the conveying mechanism does not require frequent replacements and will not require manual cleansing.

The front roller 26 is mounted upon the 80 shaft 28 having its ends 29 rotatably mounted in bearings in the sides of the carriage frame. The rear roller 27 is mounted upon the shaft 30 having its ends 31 rotatably mounted in bearings in the arms of the carriage frame. 85 The rear roller 27 has the centrally disposed circumferential groove 33 therein in which is mounted the sprocket 34 suitably fixed to the roller shaft 30.

Keyed to the screw 15 is the beveled gear 35 meshing with the bevel gear 36 fixed to the end of the horizontal shaft 37 rotatably mounted in bearings in the webs 38 integral with the struts 11 and 12. To the end 39 of the shaft 37 is fixed the sprocket 40 having meshed therewith the belt chain 41 which is meshed with the sprocket 34, whereby rotation of the output shaft of the source of power supply is adapted to impart rotatable movement to the screw 15 which in turn im-

parts rotatable movement to the rear roller 27, through the mechanism just previously explained.

It is understood that the rear roller 27 is 5 adapted to rotate in the direction indicated by the arrow 42 when the plaster is being conveyed from the hopper toward the front roller during a ascent of the carriage 5 which is positioned with the front roller 26 and adjacent 10 and parallel to the wall 43 being plastered.

For the purpose of scraping the conveyed 15 plaster from the belts 23, adjacent the wall 43, the scraper 44 is pivotally mounted on the bosses 45 of the downwardly extending arm 16 46 and 47 integral with the sides 7 and 8.

For the purpose of forcing the plaster, scraped from the belts 23 by the scraper 44, into the usual apertures of metal or wooden lath the upper edge 48 of the pressing plate 20 49 is positioned adjacent the lower edge of the scraper. The plaster falls by gravitation from the scraper upon the roller 50 having its ends journaled in the arms 46 and 47.

On the lower edge 51 of the pressing plate 25 are the lugs 52 received in holes in the downwardly extending arms 46 and 47 integral with the front ends of the sides 7 and 8 of the carriage frame.

On the rear surface of the pressing plate 30 49 is the rearwardly extending lug 53 intermediate the ends of the pressing plate. Pivotally connected with the lug 53, as by the pin 54, is the front end of the pitman 55 having its rear threaded end 56 received in a hole in 35 the upwardly extending finger 57 integral with the cam 58 rotatably mounted on the pin 59 suitably secured in the sides of the rectangular casting 60.

Fixed to the end of the rear roller shaft 30 40 is the spur gear 61 meshing with the idler gear 62 fixed to the stud 63 rotatably mounted in the downwardly extending arm 32, integral with the side 8 of the carriage frame. Meshing 45 with the idler gear 62 is the spur gear 64 fixed to the shaft 65 having its ends respectively, rotatably mounted in bearings in the downwardly extending arms 66 and 67 integral with the sides 7 and 8 of the carriage frame.

50 The rear end of the casting 60 is mounted upon the shaft 65. The cam 68 is fixed to the shaft 65 which is caused to rotate by the mechanism previously explained. The finger 69 integral with the cam 68 intermittently 55 engages the finger 70 of the cam 58, thereby forcing the cam to rotate in an arc, whereby the pitman 55 is intermittently forced rearwardly, thereby imparting intermittent rearward movement to the upper edge of the pivotally mounted pressing plate. When the finger 69 of the cam 68 disengages the finger 70 of the cam 58, the spring 71, fixed to the pitman 55 and the strut 13, urges the upper edge of the pressing plate forwardly, whereby 60 the plaster which falls from the scraper 44

onto the roller 50, during the rearward position of the pressing plate, is forced in contact with the wall.

The intermittent operation of the pressing plate continues during the ascent of the carriage from the lower edge to the upper edge 70 of the wall, whereby a strip of plaster in area equal to the product of the width of the front roller and the length of the pressing plate is applied from the lower edge to the upper edge 75 of the wall.

The smoothing mechanism which imparts movement to the arm 95 consists of the trowels 103 having its rear surface fixed to the rod 104 extending at right angles to the rear surface of the trowel. The outer end 105 of the rod 104 is slidably received in holes in the adjusters 106 and secured therein by the thumb screw 107 threaded in the side of the adjuster and adapted to be manually screwed inwardly in contact with the inner end of the rods, whereby the outer surface of the trowel is maintained in alignment with the outer surface of the applied plaster, after the trowel is properly adjusted.

Integral with the inner end of the adjuster 106 is the headed lug 108 slidably mounted in the forward portion of the slot 101 in the arm 102 which extends rearwardly. The rear end 109 of the arm 102 is pivotally 95 mounted upon the pin 110 in the upper end 111 of the side 8 of the carriage 5.

The front of the sides 7 and 8 of the frame 5 are diverged outwardly and forwardly from the points 72 to the points 73, whereby the distance between the portions 74 of the sides 7 and 8, parallel with the rear of the sides, is considerably greater than the distance between the rear ends of the sides. The angular plates 75 are integral with the 100 lower edges of the sides 7 and 8 and have their inner edges 76 in contact with the outer belts 23.

For the purpose of spreading the plaster from the grooved portion of the roller 27 110 onto the plates 75 so that plaster may be pressed by the pressing plate 49 onto the wall, the full width between the forward edges of the sides 7 and 8, or the mouth 8' of the carriage, the spreader arm 77 is adapted 115 to be operated successively from the side 7 to the side 8 of the frame, whereby the plaster is spread from the belts 23 to the plates 75 and the ends 78 of the front roller 26, as the pressing plate 49 and the front end or mouth 120 8' between the arms 46 and 47 of the carriage extends outwardly of the sides 7 and 8, and the frame 5, whereby the plaster may be spread on the wall 43 in the corner 43', as shown in Fig. 3.

The front end 79 of the arm 77 is fitted with the roller 80 which engages the wall 43 when the arm 77 is in a neutral position, or at right angles with the wall causing the rear end 81 to compress the spring 82 125

mounted in the casting 83, whereby the arm 77 will be forced outwardly from the casting 83 when the roller 80 disengages the wall thereby spreading the plaster from the belts 23 to the upper surface of the plates 75 and the ends 78 of the front roller 26.

In the slotted holes 84 in the sides of the arm 77 is received the pin 85 which holds the arm 77 in contact with the casting 83. The rear end 86 of the casting 83 is pivotally mounted upon the bearing 87 which is integral with the arms 19 and held in proper position by the pin 88.

Mounted upon the end 89 of the casting 83 is the arm 90 which has its end 91 connected to the casting 83 by the pin 92. The end 93 of the arm 90 is held in contact with the upright end 94 of the arm 95 by the pin 96. The bearing 97 in the arm 95 is mounted upon the pin 98 in the bosses 99 integral with the side 8 of the carriage 5. The end 100 of the arm 95 is received in the slot 101 of the arm 102 which imparts upward and downward movement to the end 100 of the arm 95 causing the end 94 of the arm 95 to urge the arm 90 toward the arm 95, thereby causing the arm 77 to move horizontally across the belts 23 and distribute the plaster upon the plates 75 and the ends 78 of the front roller 26.

Movement is imparted to the trowel 103 as by the pin 112 secured to the cam 113 fixed to the shaft 114 having mounted on its inner end the bevel gear 115 meshing with the bevel gear 116 keyed to the rotatable screw 17 whereby upward and downward movement is imparted to the arm 102 on which the trowel is mounted.

While I believe the form of the invention illustrated in the drawings and referred to in the above description, as the preferred embodiment, is the most efficient and practicable, yet realizing that the conditions concurrent with the adoption of the device will necessarily vary, I desire to emphasize the fact that changes in the details may be resorted to, when required, without sacrificing any of the advantages of the invention, as defined in the claim.

What I claim as new and desire to secure by Letters Patent is:

1. In a plastic material spreading machine, vertical frame members, a carriage slidable vertically on said members, and having a widened end, said frame members adapted to be arranged with said carriage in the corner of a walled surface, a material supply hopper on said carriage, a pressing plate, pivotally mounted on said carriage, means to operate said plate, means to convey material from said hopper to the widened end of said carriage, whereby vertical movement of said carriage and pivotal movement of said plate is adapted to spread and apply said material upon said walled sur-

face in the corners thereof, and means to operate said carriage and said plate.

2. In a device of the class described, a frame, a carriage frame slidably mounted on said first mentioned frame and having its front end widened, a supply hopper mounted on said carriage frame and having a discharge orifice at its bottom, a rear horizontal roller rotatably mounted on the rear of said carriage frame, a front horizontal roller rotatably mounted on the widened front of said carriage frame, said first mentioned frame adapted to be arranged with said front roller adjacent a walled face and with one end of said roller in said corner, a plurality of belts on said rollers, said belts being arranged in contacting relation with each other and below said discharge orifice, a pressing plate pivotally mounted on said carriage frame and positioned below said front roller, and means to operate said pressing plate whereby said plaster which falls by gravitation from said belts is pressed in contact with said walled surface and in said corner.

3. In a device of the class described, a frame, a carriage frame slidably vertically on said first mentioned frame and having its front end wider than its rear end, means to slide said carriage frame on said first mentioned frame, a supply hopper mounted on said carriage frame and having a discharge orifice therein, a rear horizontal roller rotatably mounted on the rear of said carriage frame, a front horizontal roller longer than said rear roller rotatably mounted on the front of said carriage frame and adapted to be positioned adjacent the wall of a room and adjacent the corner thereof, conveying means on said rollers and arranged below said discharged orifice, means to rotate said rear roller whereby plaster discharged from said orifice is conveyed by said conveying means to said front roller adjacent said walled surface, a pressing plate pivotally mounted on said carriage frame and positioned below said front roller, means to operate said pressing plate whereby said plaster which falls by gravitation from conveying means is pressed in contact with said walled surface, and means to spread said plaster from said conveying means into said corner.

ENRICO MORELLI.
